MULTIRANGE CONVERTER CIRCUITS

Murray G. Clay, Hasbrouck Heights, N. J., assignor to Radio Corporation of America, a corporation of Delaware

Application October 20, 1934, Serial No. 749,186

2 Claims. (Cl. 250—20)

My present invention relates to converter networks of superheterodyne receivers, and is more particularly directed to a converter network having a local oscillator operative over a frequency 5 range below the signal frequency range when the network is used to receive short wave signals.

Conventional superheterodyne receivers operative over the broadcast signal range (550 to 1500 k. c.) utilize a local oscillator frequency range 10 which is above the signal range and constantly differs therefrom by the selected operating intermediate frequency. For example, when the intermediate frequency is of the order of 450 k. c., the oscillator range would be 1000 to 1950 k. c. 15 It has not been considered advisable to operate the oscillator below the signal range because such operation necessitates an impractical oscillator frequency range ratio in order to reach the higher frequency end of the range.

20 This conventional broadcast band practice has been carried into short wave range reception. For example, in multi-range receivers utilizing converter networks capable of being switched from the broadcast band into a short wave band, say 25 8 to 23 megacycles, the local oscillator range has been selected to lie above the signal range in any selected band. While satisfactory for reception in the broadcast band, this mode of operation proves disadvantageous when operating over the 30 short wave bands.

Now I have found that the undesirable effects, appearing as selectivity and conversion gain losses, which occur at the short wave ranges when operating with a local oscillator range above 35 the signal range are due to the reactive nature of the load on the oscillator anode. Briefly, I have established the fact that when the oscillator frequency range is above the signal range in the reception of short waves, the load on the oscillator anode is essentially inductive. The effect 40 of this inductive load is to introduce degeneration into the signal input circuit with attendant decreased gain and broadened tuning.

45 Further investigation revealed that the inductive nature of the oscillator anode load could be rendered capacitative by operating the oscillator over a range below the signal range for short wave reception. Such a capacitative load introduced regeneration into the signal input circuit, 50 and resulted in increased gain and greater sharpness of tuning.

Accordingly, it may be stated that it is one of the prime objects of my present invention to provide a converter network adapted for operation 55 over a short wave band, the network having its

local oscillator circuit constants chosen so that the load on the oscillator anode is essentially capacitative over the band whereby increased sharpness of tuning of the signal input circuit of the network is secured as well as increased 5 gain.

Another important object of the present invention is to provide a converter network adapted for operation over the broadcast band and a short wave band, the network having its local 10 oscillator circuit constants so chosen that the oscillator frequency range in the broadcast band is above the signal frequency range, and the circuit constants of the local oscillator being so chosen for operation over the short wave band that the load 15 under the oscillator anode is essentially capacitative.

Another object of the invention is to provide a converter network for a superheterodyne receiver, and particularly one of the pentagrid converter type, the network being arranged for operation over a plurality of frequency ranges, one of said ranges covering a band of the order of 500 to 1500 kilocycles and the other range covering a band of frequencies of the order of 8 to 23 25 megacycles, the circuit constants of the local oscillator circuit of the converter network being chosen so that the oscillator frequency range is above the signal frequency range in the second of said bands.

Still other objects of the invention are to improve generally the efficiency of first detector and local oscillator circuits of superheterodyne receivers, and more especially to provide such circuits which are not only reliable in operation, 35 but economically constructed and assembled in radio receivers.

The novel features which I believe to be characteristic of my invention are set forth in particularity in the appended claims, the invention 40 itself, however, as to both its organization and method of operation will best be understood by reference to the following description taken in connection with the drawing in which I have indicated diagrammatically a circuit organization 45 whereby my invention may be carried into effect.

Referring now to the accompanying drawing there is shown the circuit details of the local oscillator and first detector networks of a superheterodyne receiver. The receiver is of the multi-range type, but for the sake of simplicity of disclosure the signal collector, which may be any well known type of antenna, and one or more stages of tuned radio frequency amplifica- 50 55

tion have been omitted. Those skilled in the art will understand that the collected signal energy, whatever the frequency range operated in, will be amplified and then impressed upon the tunable signal input circuit of the converter tube 13. The intermediate frequency energy output of tube 10 is transmitted to an intermediate frequency amplifier 11 through the coupling network M_1 which is tuned to the operating intermediate frequency. The amplified intermediate frequency energy is transmitted to a second detector, and the detected energy may then be amplified in one or more stages of audio frequency amplification, and finally reproduced.

15 The tube 10, for the purpose of explaining the present invention, is of the well known pentagrid converter type. This type of tube includes a cathode K, shown as of the indirectly heated type, a plate P, and five grids 1 to 5 inclusive disposed between the cathode K and the plate P. This type of tube, when using an indirectly heated cathode, is known by the designation RCA 2A7; when utilizing a filament cathode it is known by the designation RCA 1A6. The signal input circuit of tube 10 comprises a variable tuning condenser C_1 having its high alternating potential side, or stator plates, connected to the signal input grid 4. The rotor plates of the tuning condenser are grounded.

30 A plurality of inductance coils are provided in the input circuit and a switching arrangement is used to connect a desired one of the coils across the tuning condenser C_1 . In the interests of simplicity of disclosure, only two coils 35 L_1 and L' are shown. The wave band selector switch 12, connected to the stator side of the tuning condenser, is adapted to be connected to the high alternating potential side of either of the inductance coils. The low alternating potential sides of the coils are connected together, and the common connection point is connected to ground through a direct current blocking condenser 13. The low alternating potential side of coils L_1 and L' is also connected to a source 45 of negative grid bias, and this source may be the usual automatic volume control (AVC) source employed to minimize fading effects.

This AVC network, as those skilled in the art know, is connected to the signal grid through 50 a resistor 14, the condenser 13 usually being disposed between ground and the connection point through the AVC network. The plate P of tube 10 is connected to a source of positive voltage B, which may be the usual voltage supply resistor in the power supply network, through the 55 tuned primary circuit 14 of the coupling M_1 .

The primary and secondary circuits 14 and 55 15 of coupling network M_1 are tuned to the operating intermediate frequency, and may have 60 a band pass characteristic. Grids 3 and 4 function as screen grids, and are jointly connected to a source of positive voltage, and it will be understood that this source of voltage may be derived from the same supply resistor that the 65 source B is derived from. The grounded cathode K includes in its grounded lead the usual biasing network 16, and it will be understood that the electrodes including the cathode K, the signal grid 4 and the plate P cooperate with their 70 associated circuits to provide the converter, or first detector, network of the receiver.

The local oscillator electrodes of tube 10 include the cathode K, the oscillator grid 1, and the grid 2 which functions as the oscillator anode 75 electrode. While the electrode 2 has been con-

ventionally represented as a grid, it will be understood that its construction in actual practice will follow that usually employed in the commercial 2A7 form. The oscillator anode 2 is connected by lead 20 to a source of positive voltage, and this source of voltage may be the source B, the oscillator anode being connected to point B through a path which includes the resistor 21 having a magnitude depending upon the value to which it is desired to reduce the voltage from source B for use in connection with the oscillator anode. A pair of feedback coils L_3 and L'_3 have a common terminal connected to lead 20, and their free opposite terminals may be alternatively connected to resistor 21 through a selector switch 30. 15

The tunable local oscillator circuit comprises the tuning condenser 40 which has its rotor plates grounded, and its stator plates connected to the oscillator grid 1 through a path which includes condenser 41, resistor R_0 , the latter being shunted 20 by the oscillator grid condenser C_0 .

The tunable oscillator circuit includes coils L_2 and L'_2 , the coils have a common terminal connected to the grounded side of tuning condenser 40, and the free terminals of the coils being 25 adapted for selective connection to the stator side of condenser 40 by means of a selector switch 50. The rotors of the tuning condensers C_1 and 40 are arranged for mechanical uni-control, and this is represented by the dotted lines designated by 30 "Tuner". Of course it will be understood that the rotors of the various tunable radio frequency amplifiers, not shown, and which precede tube 10, may also be uni-controlled with the rotors of the condensers C_1 and 40. 35

The selector switches 12, 30 and 50 are the wave band changing switches, and they can be uni-controlled in any manner well known to those skilled in the art. It is sufficient for the purposes of this application to point out that when switch 40 12 is connected to coil L_1 , then switch 50 is connected to coil L_2 , and switch 30 is connected to coil L'_3 . As shown in the drawing the wave changing switches, or range changing switches, have been adjusted to have the receiving network 45 operate over the short wave range of the receiver. When the selector switches are connected to coils L'_1 , L'_2 and L'_3 , then the receiver is to be understood as operating in a frequency range, such as the broadcast range which covers 550 to 1500 50. k. c. By way of example it is pointed out that the short wave range may be one covering 8 to 23 megacycles.

Of course any other desired type of multi-range construction may be utilized. The relative magnitudes of the inductance coils are chosen according to the frequency ranges which are to be covered. Merely by way of approximation it is pointed out that the ratio of the sizes of the coils in each of the circuits, for the ranges given above, 60 is about 64 to 1. 65

The intermediate frequency to be employed may be varied to suit the desire of the set designer. By way of illustration let it be assumed 70 that the operating intermediate frequency is of the order of 450 k. c. With this value of intermediate frequency, and assuming that the wave changing switches have been thrown into position to operate in the broadcast band of 550 to 1500 k. c., the frequency range of the local oscillator will be from 1005 k. c. to 1950 k. c. Of course, the local oscillator circuit is adapted to properly "track" with the tunable signal circuit so that the energy produced in circuit 14 has a 75

frequency which is substantially constant over the entire frequency range operated over.

Considering the operating of the frequency changer network shown over the broadcast band, it is sufficient to point out that by virtue of electron coupling within tube 10 a mixing function takes place. It is not believed necessary to include in this application the theory of operation of a mixer tube of the 2A7 type. It is believed sufficient to point out that by virtue of the coupling between the oscillator anode electrode 2 and the tunable circuit of the oscillator grid 1, the electron stream flowing from the cathode K to the signal grid 4 has impressed upon it energy of the frequency of the tunable oscillator circuit. The signal grid 4 has impressed upon it the desired signal frequency, and by virtue of the electron coupling phonomenon there is produced in the circuit 14 the difference frequency desired.

Over the broadcast frequency range it has been customary to operate superheterodyne local oscillator circuits at frequencies higher than those of the desired signals in order to produce the intermediate frequency employed. While it was well known that similar operation could be secured by operating the local oscillator below the signal range, it was realized that for the reception of low frequency signals such a procedure was inadvisable.

It has been known that it required an impractical oscillator frequency range ratio in order to reach the higher frequency end of the band, when a range of oscillator frequencies was employed in broadcast band reception which is below the signal frequency range. For this reason local oscillator circuits in multi-range receivers have been operated above the desired signal frequency range through the broadcast band, and this practice has been carried into short wave operation under the impression that the practice is advantageous in the latter type of operation.

However I have found that this is not the case, and that what is apparently desirable and normal for reception in the broadcast band is detrimental and highly undesirable in the short wave ranges. Without entering into any analytical discussion, it can be stated that there is an appreciable mutual conductance between grids 4 and 2 of the order of possibly a hundred micro-mhos, and this is negative in sign. That is, a positive increment of voltage on the signal input circuit will decrease the current in the oscillator anode circuit. Hence, an inductive load under the oscillator anode will reflect positive conductance into the signal grid circuit, and a capacitative load will reflect a negative conductance into the same signal grid circuit.

Now, when the oscillator frequency is below the signal frequency in the short wave range the load under the oscillator anode is capacitative. In other words, when the receiver is adjusted to operate in a short wave range, say between 8 and 23 megacycles, the load under oscillator anode 2 is essentially inductive if the oscillator frequency is above the signal frequency; this load is capacitative in nature if the oscillator frequency is below the signal frequency.

It will therefore be appreciated that if the oscillator frequency is above the signal frequency in the short wave range, degenerative effects will be introduced into the signal input circuit because of the essentially inductive load under the oscillator anode 2. These degenerative effects will result in decreased gain and broadened tuning.

On the other hand by maintaining the local oscil-

lator frequency below the signal frequency, the load under the oscillator is kept essentially capacitative with consequent regeneration into the signal grid circuit. This results in increased gain and greater sharpness of tuning.

The load on the oscillator anode 2 which is considered as reflected into the signal grid circuit includes coils L₂ and L₄ tuning condenser 40, the oscillator grid resistor R₆ and the oscillator grid condenser C₆. Hence, and assuming that the operating intermediate frequency is still 450 k. c. when the receiver is operated over the short wave range, the selector switches being connected as shown in the drawing, the local oscillator frequency range will be from 7.55 mvc. (7550 k. c.) to 22.55 mvc. (22,550 k. c.) It is assumed that the signal frequency range is from 8 to 23 megacycles in the case of the last named oscillator frequency range. By operating over this lower oscillator frequency range the load on the oscillator anode will be maintained essentially capacitative, and it has been found that the effective conversion gain, as well as the sharpness of tuning, is considerably increased by employing this relation between signal frequency range and oscillator frequency range. Since the percentage frequency difference becomes less for higher frequency operation the advantage of the lower oscillator frequency range becomes much greater with increase in frequency. Twenty meter operation has shown an experimental advantage of about 4 to 1 in conversion gain, with a marked improvement in radio frequency selectivity, while, at the same time there was no appreciable difference in oscillator frequency coverage on the shorter wave bands.

It is to be clearly understood that the present invention is not limited to the case where operation may be over the broadcast band and a band of the order of 8 to 23 mvc. In its essence the present invention comprises operating the local oscillator through a frequency range which is lower than the signal frequency range when the band over which the receiver operates is such that the load on the oscillator anode would be essentially inductive were the oscillator frequency range above the signal range. Again, the pentagrid converter tube 10 may be replaced by separate detector and oscillator tubes since the same beneficial effects of this invention have been obtained with separate converter and oscillator operation due to the inevitable coupling between the two circuits.

There also may be cases where the high leakage reactance in the oscillator circuit, due to low mutual between the feedback and tunable oscillator circuit coils, may cause the load under the oscillator anode to be inductive regardless of whether the oscillator circuit is tuned above or below the signal frequency circuit. However, even in this situation the degeneration and loading effects would be considerably less at the higher frequencies in the short wave range when the oscillator circuit is tuned through a frequency range below the signal frequency range. In general, the present invention will be seen to provide a method of minimizing to a great extent the degenerative effects introduced into the signal input circuit of a converter network by an inductive load on the oscillator anode, when the converter network is operated in the short wave range, and the method involves the simple step of operating the local oscillator circuit through a frequency range below the operating signal frequency range.

While I have indicated and described several systems for carrying my invention into effect, it will be apparent to one skilled in the art that my invention is by no means limited to the particular organization shown and described, but that many modifications may be made without departing from the scope of my invention, as set forth in the appended claims.

What I claim is:

- 10 1. In a frequency changer network for a superheterodyne receiver, a single electron discharge tube provided with an oscillator electrode section and a detector electrode section, both sections having a common cathode, a tunable signal input circuit connected to the input electrodes of said detector section, a tunable oscillator circuit connected to the electrodes of said oscillator section, said signal circuit including means for tuning it over a pair of widely separated signal frequency ranges, means in the oscillator circuit for tuning it over a pair of correspondingly widely separated oscillator frequency ranges, the circuit elements of the local oscillator circuit having magnitudes such that the oscillator frequency range is above the lower one of said pair of signal ranges when operating in the lower signal range and the oscillator frequency range is below the upper one of said signal ranges when operating in the latter range.
- 20 25 30 2. In a superheterodyne receiver a tunable

first detector circuit including means for rendering the detector circuit tunable over the broadcast band, a tunable oscillator circuit including means for rendering the oscillator circuit tunable through a range of frequencies spaced from, and above, the broadcast band and differing therefrom by the desired operating intermediate frequency, additional means operatively associated with the tunable detector circuit for rendering the detector circuit operative over a short wave range of frequencies, additional means operatively associated with said oscillator circuit to render the oscillator circuit tunable over a frequency range spaced from, and below, the short wave range and differing therefrom by the said intermediate frequency, an electron discharge tube having a cathode and cold electrode connected to the detector circuit, at least two auxiliary cold electrodes in said tube, one of said auxiliary electrodes and said cathode being connected to said oscillator circuit, said other auxiliary electrode being reactively coupled to said one auxiliary electrode, and said oscillator circuit introducing regenerative effects into said tunable detector circuit over the entire short wave range whereby the gain in said detector circuit is considerably increased and the selectivity is effectively increased.
